UNITED STATES PATENT OFFICE.

JOHN F. HEMENWAY, OF NEW YORK, N. Y.

CLOTHES-WRINGER.

1,205,201.

Specification of Letters Patent. Patented Nov. 21, 1916.

Application filed April 1, 1916. Serial No. 88,248.

To all whom it may concern:

Be it known that I, JOHN F. HEMENWAY, a citizen of the United States, residing at New York city, in the county of New York and State of New York, have invented certain new and useful Improvements in Clothes-Wringers, of which the following is a specification, reference being had therein to the accompanying drawing.

10 This invention relates to certain new and useful improvements in clothes wringers, and more particularly to pressure releasing means for the pressure rolls, the object being to provide means for releasing the top bar of 15 the wringer frame carrying the pressure screws so as to instantaneously release the pressure on the pressure roll.

Another object of my invention is to provide a wringer with a movable top bar which 20 is held in position with the slotted upper ends of the side bars by a bowed spring, the ends of which extend into the horizontal slots of the vertically disposed portions of U-shaped member, carried thereby, said 25 spring being reduced in width adjacent the ends so that when the reduced portions are moved into vertical alinement with the vertically disposed slots which register with the horizontally disposed slots of the vertically 30 disposed members, the top bar will be allowed a limited upward movement.

Other and further objects and advantages 35 of the invention will be hereinafter set forth and the novel features thereof defined by appended claims.

In the drawing, Figure 1 is a side elevation of a wringer showing the application of my improved construction of pressure releasing means thereto. Fig. 2 is a top plan 40 view, and Fig. 3 is an end elevation.

Like numerals of reference refer to like parts in the several figures of the drawing.

In carrying out my invention I employ a wringer frame composed of a pair of slotted 45 side bars 1 and 2 connected together adjacent their lower end by cross bars 3 and provided with superposed bearings 4 and 5 in which are mounted shafts 6 and 7 carrying coöperating pressure rolls 8 and 9, said 50 shafts being provided with gears, not shown, and inclosed by casings 10.

Mounted on top of the upper bearings 5, is a cross bar 11 which is slidably mounted within the slotted portions of the side bars 1 and 2 and upon which the free ends of a 55 pressure spring 12 are mounted, said spring

being carried by a pressure bar 13 which is provided with bearing plates 14 adjacent the ends thereof.

Slidably mounted within the upper ends 60 of the slotted portions of the side bars 1 and 2 is a top bar 15 provided with threaded boxes 16 adjacent its ends in which are mounted the threaded portions of pressure screws 17 which engage the bearings 14 of 65 the pressure bar 13 so as to adjust the pressure on the pressure rolls.

Secured to the upper ends of the side bars 1 and 2 of the wringer frame are U-shaped members 18 which are provided with vertically disposed portions 19 having horizontally disposed slots 20 from which extend vertically disposed slots 21 whereby a substantially inverted T-shaped slot is formed 70 in each vertically disposed portion.

Arranged on the top bar 15 is a bowed spring 22 which is provided with substantially horizontally disposed end portions having oppositely disposed notches forming substantially T-shaped portions 23 at 80 the ends of the bowed spring, the heads of the T being adapted to normally rest within the horizontally disposed slots of the vertically disposed portions 19 of the U-shaped members so as to prevent the top bar 15 85 from moving vertically whereby the same is held in rigid position within the side bars 1 and 2 of the wringer frame so as to allow the pressure screws 17 carried thereby to exert a pressure on the pressure bar 13. 90 The ends of the springs are slotted, as shown at 24, through which the pressure screws 17 pass so as to allow the spring to have free movement in respect to the screws whereby the top bar when released, will be allowed 95 to move vertically.

When the pressure releasing mechanism is in the position shown in Figs. 1 and 2, and is desired to instantaneously release the pressure on the pressure rolls, by striking the 100 bowed spring 22, the same will be elongated so as to force the heads of the T-shaped ends 23 out through the slots 20 which will bring the reduced portions or the stems of the T in vertical alinement with the vertical slots 105 21 of the extensions 19 so as to allow the top of the springs to move vertically within the slots 21 which allows the top bar to move vertically to release the pressure on the pressure roll.

110 From the foregoing description, it will be seen that I have provided a clothes wringer

in which the top bar is normally held in position with the side bars of the wringer frame by a bowed spring having substantially T-shaped ends which are adapted to 5 coöperate with substantially T-shaped slots formed in the vertically disposed portions of the members carried by the side bars so as to allow the top bar to have a limited vertical movement when the reduced portions of the 10 springs are brought into alinement with the vertically disposed slots which will instantaneously release the pressure on the pressure rolls of the wringer, and at the same time will prevent the top bar from becoming detached from a wringer frame.

I claim:

1. A wringer comprising a frame, having pressure rolls and pressure means mounted therein, a movably mounted top 20 bar mounted within said frame, U-shaped members carried by the side bars of said wringer frame having vertically disposed portions provided with substantially inverted T-shaped slots, pressure screws carried by the top bar, a bowed spring provided with slots to receive said pressure screws, said bowed spring having horizontally disposed T-shaped ends mounted within the slots of said vertically disposed 25 portion and normally holding said top bar in position within said frame.

2. A clothes wringer comprising a frame having a movably mounted top bar carrying pressure screws, members carried by the 30 side bars of said frame provided with vertically disposed portions having inverted T-shaped slots, and a bowed spring carried by said top bar and having substantially T-shaped ends coöperating with said slots 35 for holding said top bar in position in said frame and for allowing said top bar to move vertically by the lateral movement of the ends of said spring.

3. A clothes wringer comprising a frame 45 having pressure rolls and pressure means mounted therein, a top bar carrying pressure screws, members carried by the side bars of said frame provided with vertically disposed portions having substantially inverted T-shaped slots, a bowed spring having slots to receive the pressure screws of said top bar and provided with substantially horizontally disposed T-shaped ends, the heads of said T shape portion being 50 adapted to normally rest within the horizontally disposed slots of said vertically disposed portions for holding said top bar within said frame.

4. A clothes wringer comprising a frame 60 having pressure rolls and pressure means mounted therein, a top bar for said frame having pressure screws for adjusting said pressure means, members secured to the side

bars of said frame having vertically disposed portions provided with substantially inverted T-shaped slots, and a bowed spring carried by the top bar having T-shaped ends coöperating with said T-shaped slots for holding and releasing said top bar.

5. A clothes wringer comprising a frame 70 having pressure rolls and pressure means mounted therein, U-shaped members embracing the side bars of said frame having vertically disposed portions provided with horizontal and vertical slots, a top bar 75 mounted in said frame and capable of moving vertically therein, a bowed spring carried by said top bar provided with slots, pressure screws carried by the top bar extending through said slots, said spring having reduced ends provided with oppositely disposed notches forming heads, the heads of said spring being seated within the horizontally disposed slots of said vertically disposed portions, the ends of said spring 85 being capable of being moved laterally by exerting a downward pressure thereon to throw the reduced portions thereof in alinement with the vertical slots of the vertically disposed portions to allow said top bar to 90 move vertically within said frame.

6. A clothes wringer having pressure rolls and pressure means mounted therein, a movably mounted top bar carrying pressure screws coöperating with said pressure means, U-shaped members secured to the side bars of said frame having vertically disposed portions provided with substantially inverted T-shaped slots, a bowed spring carried by said top bar having substantially T-shaped heads coöperating with the T-shaped slots of said vertically disposed portions for holding and releasing said top bar.

7. A clothes wringer comprising a frame 105 having pressure rolls and pressure means mounted therein, a top bar for said frame having pressure screws for adjusting said pressure means, members secured to the side bars of said frame having vertically 110 disposed portions provided with horizontally disposed slots registering with a vertically disposed slot, and a bowed spring having its ends seated within the horizontally disposed slots of said vertically disposed portions, and provided with reduced portions adapted to enter the vertically disposed slots for allowing said cross bar to move vertically within the wringer frame.

In testimony whereof I hereunto affix my 120 signature in the presence of two witnesses.

JOHN F. HEMENWAY.
